UNITED STATES PATENT OFFICE

99,382

DESIGN FOR A COMBINATION BACK AND ARM REST FOR A COUCH OR SIMILAR ARTICLE

Arthur Wesley, Chicago, Ill., assignor to Burton-Dixie Corporation, Chicago, Ill., a corporation of Delaware

Application March 7, 1936, Serial No. 61,513

Term of patent 7 years

To all whom it may concern:

Be it known that I, Arthur Wesley, a citizen of the United States, residing at Chicago, in the county of Cook and State of Illinois, have invented a new, original, and ornamental Design for a Combination Back and Arm Rest for a Couch or Similar Article, of which the following is a specification, reference being had to the accompanying drawing, forming a part thereof.

In the drawing:—

I claim:

The ornamental design for a combination back and arm rest for a couch or similar article, as shown.

ARTHUR WESLEY.
